DESIGN FOR A HANDKERCHIEF

George M. Logan, Jr., New York, N. Y.

Application June 17, 1939, Serial No. 85,537

Term of patent 3½ years

To all whom it may concern:

Be it known that I, George M. Logan, Jr., a citizen of the United States, residing in the Borough and county of Bronx, city and State of New York, have invented a new, original, and ornamental Design for a Handkerchief, of which the following is a specification, reference being had to the accompanying drawing, forming a part thereof, in which the single figure is a plan view showing one corner of a handkerchief embodying my new design, the balance of the handkerchief being free from ornamentation.

I claim:

The ornamental design for a handkerchief, as shown and described.

GEORGE M. LOGAN, JR.
